(57) **CLAIM**

The ornamental design for a computer device having a front bezel for a memory module receptacle, as shown and described.

DESCRIPTION

FIG. 1 is a partial front perspective view of the design for the computer device having a front bezel for a memory module receptacle;

FIG. 2 is a front elevational view of the design for the computer device having a front bezel for a memory module receptacle as illustrated in FIG. 1;

FIG. 3 is a right side elevational view of the design for the computer device having a front bezel for a memory module receptacle as illustrated in FIG. 1, the left side being substantially the same as the illustrated right side; and

FIG. 4 is a partial front perspective view of the design for the computer device having a front bezel for a memory module receptacle as illustrated in FIG. 1, wherein the front bezel is illustrated in context of a rack mountable computer, e.g., a server, that can be mounted in a rack computer system; and, FIG. 5 is a front elevational view of the design for the computer device having a front bezel for a memory module receptacle as illustrated in FIG. 4, wherein the front bezel is illustrated in context of a rack mountable computer, e.g., a server, that can be mounted in a rack computer system.

In these drawings, the solid lines illustrate the claimed ornamental design, whereas the broken lines illustrate environmental features that form no part of the claimed ornamental design of the subject embodiment.
